GEORGE W. CODRINGTON, OF LAKewood, OHIO

REVERSING STARTER MEANS FOR INTERNAL COMBUSTION ENGINES

Application filed January 19, 1931. Serial No. 509,709.

This invention relates to starting means for reversing internal combustion engines. Particularly in marine practice it becomes necessary that the propulsion engine be started and stopped in reverse in the shortest possible time, and hence as conveniently as possible. It has been generally the practice heretofore to accomplish such maneuvering control by air starting means, which, however, involves the use of a system of valve sets, such apparatus becoming more complicated as the multiplicity of engine cylinders increases. It is more convenient, therefore, to start the engine in either direction by simply putting its crank shaft in motion in the desired direction, and such a procedure is of increasing desirability as the cylinder multiplicity increases. It is the object of this invention to provide starting means employing power from an auxiliary such as an electric motor which may be continuously driven during the standby period and to apply this power in a manner much more directly upon the engine crank shaft.

Briefly the invention comprises the use of the well-known Bendix type of drive, including pinions acting directly on the flywheel gear or other like engine part. The invention includes the employment of a pair of such Bendix pinions, one left-hand and one right-hand, for selective engagement with the gear, together with means providing for instantaneous control of such optional engagement. More specifically the two pinions according to this invention are mounted, in aligned relation, upon a common shaft, which shaft is reversible at the will of the operator through suitable reversing gear and associated clutch means, which in turn is driven by the continuously running motor.

The invention also includes the provision of inertia means rigidly associated with the motor whereby the initial starting effort may be increased by accumulated inertia.

The exact nature of this invention together with further objects and advantages thereof will be apparent from the following description taken in connection with the accompanying drawing which is a largely conventional showing of the combination of elements

which comprise the invention parts appearing in section to show details of construction.

With reference now to the drawing, 1 is the flywheel of the engine to be controlled, which flywheel carries a gear 2 engageable by either of a pair of pinions 3 and 4, which pinions are slidably mounted upon a shaft 5.

The shaft 5 is mounted in suitable bearings indicated in the frame-housing 6.

Secured upon the shaft 5 is a gear 7 meshing with the pinion 7 on a shaft 8 which shaft is also mounted in the frame 6. Secured with the frame 6 is a motor indicated at 9 having a shaft 10 which, if the motor be electric, may be the motor armature shaft. A flywheel 11 is secured upon the shaft 10. The shafts 8 and 10 which may be aligned, extend within the box 12. Therein is provided reversing gears and a pair of associated clutches; whereby the shaft 8 may receive drive from the shaft 10 in either the same or reverse direction dependent upon the manipulation of the clutches. The exact details of such arrangement are immaterial and the described result may be accomplished in a number of ways.

For example, the well-known reversing gear for interposition between the engine and propeller of a motor boat, would be suitable. Suffice it then to say that the reversing gear provides that the shaft 10 operating in one direction may be caused to operate the shaft 8 in either direction subject to the control of a lever 13. This lever may be arranged for control by a handle 14 pivoted as at 15, through a link 16. The handle 14 is, of course, located in a position convenient to the engineer and is movable from its shown or central position wherein the shaft 8 is un-driven, to the left or right to cause the shaft 8 to be driven in corresponding ahead or astern direction.

The drive of each of the pinions 3, 4, from the shaft 5, is by an arrangement well-known by the term Bendix. Thus this arrangement includes for the pinion 4 a helical mounting of the pinion on the shaft so that the pinion will have motion longitudinal of the shaft coincident with rotational motion theron. A spring 17 tends to maintain the pinion 4 in the position shown, clear of the gear 2 and

rotational drive between pinion and shaft includes the spring 17 when the pinion is moving along the shaft. The helical connection includes a stop engaged by the pinion 5 after shifting of the latter to mesh with the gear 2 so that the drive from shaft to pinion and hence from shaft to flywheel is positive when the pinion is meshing with the gear 2, so long as the drive is in a direction tending 10 to advance the pinion against the stop. As soon, however, as the engine starts, so that the flywheel tends to overrun the pinion in the starting direction, the pinion moves back on its helix to the position shown where it is 15 retained by the spring 17. Thus when the shaft 5 is driven in one direction the pinion 4 will move forward to engage the gear 2, but when the shaft 5 is moving in the opposite direction there is no such tendency. The 20 teeth of the pinion 14 are undercut as indicated to provide easy engagement with the gear 2 when the pinion is running in its starting direction.

The opposite pinion 3 is similarly mounted 25 upon the shaft 5 except that the arrangement of its Bendix drive is such that it will engage the gear when the shaft 5 is driven in the opposite direction from that in which the pinion 4 engages the gear. Consequently the 30 teeth of the pinion 3 are undercut oppositely from those of the pinion 4 and those of the gear 2 are undercut at both ends.

It will be apparent that when the motor 9 is operating the shaft 10, manipulation of 35 the handle 14 will cause the shaft 5 to be driven in either direction to cause the corresponding one or the other of the pinions to engage the gear 2 and start the engine in the corresponding ahead or astern direction. By 40 the described gearing between shafts 5 and 8, the shaft 5 moves with lesser speed but greater force than the shaft 8. In operation, before it is desired to start the engine in either direction, the motor 9 is started to set the 45 shaft 10 in motion, building up energy in the flywheel 11. Thereafter when the handle 14 is manipulated to cause starting of the engine in either direction, the energy stored in the flywheel 11 becomes available in addition to 50 that of the motor itself, to act upon the engine flywheel with starting effect in the desired direction of the latter.

What I claim is:

1. Starting means for a reversing internal 55 combustion engine and comprising a motor, a pair of Bendix pinions respectively arranged for left and right hand starting engagement with the starting gear of said engine, a drive between said motor and said pinions and including a reversing connection 60 and associated clutch means for controlling said drive to cause either pinion to engage said gear without stopping said motor.

2. Starting means for a reversing internal 65 combustion engine and comprising a motor,

a pair of aligned Bendix pinions respectively arranged for left and right hand starting engagement with the starting gear of said engine, a drive between said motor and said pinions and including a reversing connection 70 and associated clutch means for controlling the direction of said drive to cause either pinion to engage said gear without stopping said motor.

3. Starting means for a reversing internal 75 combustion engine and comprising a motor, a pair of Bendix pinions respectively arranged for left and right hand starting engagement with the starting gear of said engine, a drive between said motor and said 80 pinions and including a reversing connection and associated clutch means for controlling said drive to cause either pinion to engage said gear without stopping said motor, and flywheel means arranged in said drive 85 between said motor and said clutch means.

In testimony whereof I hereby affix my signature.

GEORGE W. CODRINGTON.
